ADDISON E. AUGUSTINE, OF HACKENSACK, NEW JERSEY, ASSIGNOR TO CHESTER MACHINE CO. INC., OF NEW YORK, N. Y., A CORPORATION OF NEW YORK.

BALANCED CAM SHAFT.

1,404,183.

Specification of Letters Patent. Patented Jan. 24, 1922.

Application filed November 18, 1919. Serial No. 338,815.

To all whom it may concern:

Be it known that I, ADDISON E. AUGUSTINE, residing at Hackensack, in the county of Bergen and State of New Jersey, have 5 invented certain new and useful Improvements in Balanced Cam Shafts, of which the following is a specification.

This invention relates to a balanced cam shaft.

10 In machines in which cams are employed for controlling the operation of different elements of the machine the cams almost necessarily produce a preponderance of weight at one side of the rotating axis of their carrying shaft and this weight naturally tends to gravitate to the lowest point, thus causing at times an operation of one or more elements of the machine after the driving power has been cut off from said shaft and 15 the machine is supposed to be at rest.

Also, certain of the levers, rollers, etc. which bear against and cooperate with the cams frequently induce rotation of the cam shaft to the same undesirable result.

25 It is the object of this invention, therefore, to overcome this difficulty by providing means whereby the cam shaft is at all times substantially balanced and no tendency is present for rotating the shaft except that 30 purposely applied by the appropriate driving mechanism.

A further more detailed object is to provide the cam shaft with a cam and means cooperative therewith for counteracting in 35 proportional power the tendency of the other cams and their cooperative parts to rotate the shaft.

Other objects and aims of the invention, more or less specific than those referred to 40 above, will be in part obvious and in part pointed out in the course of the following description of the elements, combinations, arrangements of parts and applications of principles, constituting the invention; and 45 the scope of protection contemplated will be indicated in the appended claims.

In the accompanying drawings which are to be taken as a part of this specification, and in which I have shown merely a preferred form of embodiment of the invention:—

Figure 1 is a transverse sectional view through a cam shaft having cams thereon

and cooperative features arranged in accordance with this invention, and 55

Figure 2 is a top plan view of the mechanism illustrated in Fig. 1.

Referring to the embodiment illustrated in detail in the drawings, the reference character L indicates the cam shaft and G indicates one of the usual cams which is fixed to the shaft in position for operating a lever 1. The lever 1 may be pivotally mounted, as at 2, in any appropriate support as for instance the portion 3 of the 60 frame work of the machine. This lever, as illustrated, includes an arm 4 carrying a rod 5 which extends to some foreign point for operating a given feature of the machine of which the cam shaft forms an essential element. Other cams, as 6 and 7, may be fixed to the shaft L and these may also have levers, corresponding to the lever 1, or they may be provided with other appropriate cooperative means, as will be readily understood 65 for operating other features of the machine.

In Figure 1 a side view is given of the cam G and it will be seen that a roller 8 carried by the lever 1 rests against the surface 9 of the cam G in such manner that the 70 pressure of the roller, under the tension of the spring 10, is exerted against the surface 9 of the cam in a manner tending to rotate the cam in the direction of the arrows in said figure. 85

It will also be seen that the preponderance of weight in the cam G is such as to lend force to the same tendency.

Mounted upon the shaft L is a cam H. A lever 11 carries a roller 12 which bears 90 upon the surface of the cam H under the pressure of a spring 13. The lever 11 may be pivotally mounted, as at 14, in a portion 15 of the main frame of the machine, and the contour of the surface of the cam H with 95 which the roller 12 engages is such that the pressure of the roller against said surface produces a tendency to rotate the cam in a direction opposite at all times to the direction in which the roller 8 tends to rotate 100 the cam G and with a power which is preferably exactly proportional to the opposing power of the roller 8.

This result may, of course, be obtained in various ways, as by changing the contour 105 or size of the cam H, or by utilizing a spring

of greater or less power in the position of the spring 13. The principle involved, however, is always the same; namely, of applying to the shaft a retarding force which 5 is at all times proportional in power to the power of the roller 8 and other undesirable forces tending to rotate the shaft.

Of course it will be understood that the cam G and its lever 1 are simply illustrative 10 of any number of cams and levers which may be associated with the cam shaft for operating the various elements of the machine. These various cams and levers may be of different types and shapes but their 15 resultant tendency to rotate the shaft is always the same in kind as is illustrated by the swinging arm G and lever 1. Whatever the degree of this tendency, the cam H and its lever 11 are intended to counteract in 20 proper proportional force so that the shaft will stand at rest in any position of rotation to which it may be moved by the machine's prescribed driving mechanism.

It should be noted that incidentally the 25 presence of the cam H and lever 11 imposes substantially no additional work to be performed by the normal driving mechanism of the machine but that they simply serve to make the work to be performed of a constant 30 quantity instead of as an everchanging quantity as heretofore.

It is further to be noted that the cam H may be so shaped and positioned as to place a preponderance of its own weight in such 35 position relative to the rotating axis of the shaft L as to counteract in proportional degree the tendency of the shaft to rotate under the influence of the cam G or even under the influence of said cam G and the lever 1.

40 As many changes could be made in this construction without departing from the scope of the invention as defined in the following claims, it is intended that all matter contained in the above description or shown 45 in the accompanying drawings, shall be interpreted as illustrative only and not in a limiting sense.

Having thus described my invention, what 50 I claim as new and desire to secure by Letters Patent is:—

1. A cam shaft, a cam fixed thereto, and means to be operated by said cam, said cam and said means being cooperative for tending to rotate said shaft undesirably, the combination therewith of means to counteract and balance said tendency.

2. A cam shaft, a cam fixed thereto, and means to be operated by said cam, said cam and said means being cooperative with a 60 varying degree of power tending to rotate the shaft undesirably, the combination therewith of means to counteract said tendency with a power varying in proportion to said first mentioned power.

65 3. A cam shaft, a cam fixed thereto, and

means to be operated by said cam, said cam and said means being cooperative with a varying degree of power tending to rotate the shaft undesirably, the combination therewith of a second cam fixed to said shaft and 70 means cooperative therewith to counteract said tendency with a power varying in proportion to said first mentioned power.

4. A cam shaft, a cam fixed thereto, and means associated with said cam tending to 75 rotate said shaft undesirably, the combination therewith of means to counteract and balance said tendency.

5. The combination with a cam shaft having a plurality of cams fixed thereto of different contours, and means associated with said cams tending collectively to rotate said shaft undesirably, of means to counteract 80 said tendency.

6. The combination with a cam shaft having a plurality of cams fixed thereto of different contours, and means associated with said cams tending collectively to rotate said shaft undesirably, of means at all times operating upon said shaft to balance proportionally the effect of said first mentioned 85 means and thereby to counteract said tendency.

7. The combination with a cam shaft, a cam fixed thereto, and a follower device 95 pressing against said cam tending by its engagement with the relatively inclined surfaces of the cam to rotate the cam undesirably, of means at all times operating upon said shaft to balance proportionally the effect of said follower device and thereby to counteract 100 said tendency.

8. The combination with a cam shaft, a cam fixed thereto, and a follower device engaging said cam offering varying resistance 105 to the rotation of said shaft according to the contour of said cam, of means at all times operating upon said shaft to balance proportionally the effect of said follower device and thereby to produce a uniform resistance to 110 the rotation of said shaft.

9. The combination with a cam shaft, a cam fixed thereto, and a follower device engaging said cam, said follower device and said cam cooperating to offer varying resistance to the rotation of said shaft according to the contour of said cam, of a further cam fixed to said shaft, and means engaging said further cam at all times cooperating therewith to balance proportionally the effect of 115 said first cam and said follower device and thereby to produce a uniform resistance to the rotation of said shaft.

In testimony whereof I affix my signature in the presence of two witnesses.

ADDISON E. AUGUSTINE.
